United States Patent Office.

CARL AUGUST BIERMANN, OF WATERLOO, ILLINOIS.

Letters Patent No. 61,797, dated February 5, 1867.

IMPROVEMENT IN HEMP BREAK.

The Schedule referred to in these Letters Patent and making part of the same.

TO ALL WHOM IT MAY CONCERN:-

Be it known that I, CARL AUGUST BIERMANN, of Waterloo, in the county of Monroe, and State of Illinois, have invented a new and useful "Hemp Break;" and I hereby declare that the following is a full and clear description thereof, reference being had to the accompanying drawings, and to the letters of reference marked thereon.

The nature of this invention consists in the arrangement of a series of stationary-breaks, in combination with a series of operating ones, which latter may be operated either by hand power or any other. The arrangement of the parts is such that a continuous motion may be given to the operating breaks without interfering in the least with the feeding of the machine.

To enable those skilled in the art to make and use my improved "break," I will proceed to describe its construction and operation.

Figure 1 of the drawings is a side elevation of the improved machine.

Figure 2 is a sectional elevation of the same; and

Figure 3 is an end elevation of it.

A is a vertical post, which is erected upon and firmly braced to its foundation, B. A vertical groove within the post A furnishes bearings for the sliding or reciprocating head C. There are stationary breaks, *a*, inserted into mortises in the upper end of the post A, and projecting on either side of the said post some six or eight inches (more or less) outside of it, as clearly shown in fig. 1. These breaks should have knife edges as shown in fig. 3, and they should be arranged in pairs as also shown in the last-named figure. There should not be less than three pairs of these stationary breaks, and each pair is to be so placed that a vertical line will bisect the two breaks of a single pair, and the knife edges of them are to be directed toward each other, with, say one or two inches (more or less) between them. The different pairs of these breaks are to be just sufficiently far apart to allow the operating breaks *c*, to play up and down between them, and not to be choked up by the fibre which is being broken. These breaks, *c*, are similar in construction and operation to the stationary breaks *a*, already described: They are mortised into the sliding head C, and are carried up and down with it in a reciprocating motion. The breaks *c* are the same length as those marked *a*, and both sets of them have their outer ends, on the knife-edge sides of them, rounded off to a point on the back of the blade, so as to permit the feeding of the unbroken hemp into the breaks while the machine is in motion. A counter-shaft, D, finds its bearings in the lower portion of the post A. A crank, *d*, on one end of this shaft, is connected by means of the pitman *d*¹ with the sliding head C, to which it imparts a reciprocating motion. A driving-shaft, D¹, imparts motion to the counter-shaft D, through the medium of the cog-gearing *d*² *d*³. The shaft D² may be provided with a crank, *d*⁴, if this break is to be operated by hand, or in lieu thereof with a suitable wheel if it is to be driven by power. By setting the driving-shaft D¹ in motion, a rapid reciprocating motion will be given to the break *c*, and unbroken hemp can then be fed in by hand between the breaks *a* *c*, where it will be rapidly and thoroughly broken and prepared for the market.

Having described my invention, what I claim, is—

1. The combination and arrangement of the stationary post A, and the sliding head C, substantially as described and set forth.
2. I claim the stationary breaks *a*, and the operating breaks *c*, when constructed and operated as described and set forth.
3. I claim the combination of the sliding head C and its breaks *c*, with the stationary breaks *a*, as and for the purpose set forth.

In testimony of which invention I hereunto set my hand this tenth day of August, A. D. 1866, in presence of—

CARL AUGUST BIERMANN.
